UNITED STATES PATENT OFFICE.

ROY CHESTER TOWNSEND, OF BELOIT, WISCONSIN.

CARBURETER.

1,235,612.

Specification of Letters Patent. Patented Aug. 7, 1917.

Application filed December 21, 1915. Serial No. 68,081.

To all whom it may concern:

Be it known that I, Roy C. TOWNSEND, a citizen of the United States, residing at Beloit, in the county of Rock, State of Wisconsin, have invented a new and useful Carbureter; and I do hereby declare the following to be a full, clear, and exact description of the invention, such as will enable others skilled in the art to which it appertains to make and use the same.

This invention relates to an improved carbureter, and one of the objects of the invention is to provide a carbureter, in which low grade fuel oil may be used.

Another object of the invention is the provision of a carbureter having means for introducing air from two different sources into the mixing chamber, the air from one source being heated, while the other is not, and into which mixing chamber the low grade fuel oil or gasoline is atomized, thereby producing a combustible gasoline mixture, which may be drawn into the engine cylinder upon a suction stroke of the piston thereof.

Another object of the invention is to provide means for introducing a small quantity of water (which is thoroughly atomized) into the cold air, which cold air and atomized water, are drawn into the mixture in the mixing cylinder, to moisten the mixture, which has been found desirable, essential and practical in connection with low grade fuel oils, during high or low speed, or light or heavy loads, but especially when the engine is running under a heavy load.

Another object of the invention is to avoid the introduction of water in large particles into the engine cylinder, when the engine is running under light loads, because the explosive temperature would be too low to thoroughly consume the water and the lubrication in this case would be washed from the cylinder wall, thereby causing fast wearing upon the parts.

In practical fields the details of construction may necessitate alterations, falling within the scope of what is claimed.

The invention comprises further features and combination of parts, as hereinafter set forth, shown in the drawings and claimed.

In the drawings:

Figure 1 is a vertical sectional view through the carbureter.

Fig. 2 is a sectional view on line 4—4 of Fig. 1.

Fig. 3 is a detail view of the atomizing nozzle for the fuel oil or gasoline.

Fig. 4 is a detail sectional view of the water nozzle and its atomizing extremity. 60

Referring more especially to the drawings, 1 designates a reservoir for the fuel oil or gasoline, and formed on the interior of this reservoir is the passage 2, through which hot air from any suitable source, as indicated by the arrow *a* may pass, and thence through the tube 3 into the mixing chamber 4, which is formed on the interior of the cylindrical casing 5 of the carbureter. The tube 3 at one end is formed with an annular flange 6, which is clamped between the flanged end 7 of the casing 5 and the flange 8 of the reservoir casing, there being bolts 9 for securing the parts together. Formed in the wall 10 of the reservoir casing is a duct 11. In other words, the wall 10 is thickened or enlarged, and which thickened or enlarged portion is upon the interior of the space 2, and in the enlargement the duct 11 is formed. Referring to Fig. 4 it will be observed that the lower part of the enlargement has an integral connection at 12 with the side of the wall of the passage or space 2. Formed through this integral connection 12 is a short duct 13, 85 which forms a communication between the interior of the reservoir and the lower enlarged part or portion 14 of the duct 11, so that the fuel oil or gasoline may pass through the duct 11. Just where the narrow part of the duct 11 merges into the larger part thereof a needle valve seat 15 is formed. Coöperating with the valve seat is a needle valve 16, the threaded part 17 of which is threaded partially through the thickened wall 10, and is provided with a head 18, whereby the needle valve may be adjusted, so as to control the quantity of fuel oil or gasoline into the duct 11. The duct 11 at its upper portion terminates in angularly extending part 19, into which the tubular shank 20 of the sprayer or atomizer 21 is threaded or otherwise secured. The sprayer or atomizer is arranged, so as to extend partially into the tube 3, so that as the hot air from any suitable source is sucked or drawn through the tube 3, the oil fuel is atomized into the same, so that by the time the fuel and hot air reach the mixing chamber at *b* they are thoroughly mixed, and the fuel is broken into small particles. The casing 5 has a flange 23 at one

end, which is secured by the bolts 24 to the side of the engine cylinder, in the proper position so that the mixture from the mixing chamber 4 may be drawn or sucked in to the cylinder through the port 25. Arranged in the casing 5 transversely thereof is a shaft 26, on which a valve 27 is mounted. This shaft may be connected by any suitable means (not shown), to a suitable 10 governor mechanism (not shown), so that the shaft may be operated automatically, for actuating the valve 27, which controls the desired amount of combustible fuel into the cylinder 28. However, any suitable manually operated means may be connected to the shaft 26 for actuating the valve. The casing 5 is provided with an integral downwardly extending tubular casing 29 having a chamber 30, through which cold air from 15 any suitable source may enter as indicated by the arrow *c*. Where the casing 29 forms an integral part of the casing 5 a valve seat 31 is provided. Coöperating with the seat 31 is a disk valve 32 having a stem 33 mounted in axially arranged bearings 34 of the spiders 35, which extends across the chamber 30 of the tubular casing 29. A disk member 36 is threaded upon the shank 33 or stem, for adjusting the tension of the 20 spring 37, which is interposed between the disk member 36 and the upper spider 35. Upon the suction stroke of the piston 38 in the engine cylinder, the valve 32 is automatically unseated or opened, against the 25 tension of the spring 37, thereby drawing a charge of cold air into the mixing chamber 4, to mix with the atomized oil fuel or gasoline and the hot air from the passage 2. Secured to the side of the casing 29 is a 30 needle valve casing 40 having a duct 41 and valve seat 42. This needle valve casing 40 has a tube 43 connected to it as at 44, for conveying cold water from any suitable source into the casing at 45. A needle valve 46 has its threaded portion 47 threaded into 35 the casing 40. The thumb piece 48 may be turned for regulating the needle valve relative to its seat, for controlling the supply of cold water. A spraying or atomizing nozzle 49 is threaded at 50 into the needle valve casing 40. The nozzle 49 has its atomizing extremity disposed axially with the center of the chamber 30, so that the water passing in regulated quantities 40 through the nozzle 49, may be atomized into the cold air entering through the chamber 30, at all times responsible to the suction stroke of the piston of the engine. However, the introduction of the atomized fine 45 mist or spray of water is particularly essential when the engine is running under a heavy load. However, the atomizing extremity of the nozzle must be of such a construction that the water will be introduced 50 into the cold air in infinitesimal particles,

or in the form of an extremely fine mist, so that when the charge (which is composed of hot and cold air and atomized fuel oil and atomized or a fine mist of water) enters the combustion chamber of the engine, 70 the explosive temperature in the combustion chamber will thoroughly consume the water or moisture in the charge, without washing out the lubricant on the wall of the combustion chamber. It has been found exceedingly desirable, essential and practical 75 to introduce a small quantity of water combined with cold air into a combustible charge of gas, for moistening the same, when producing the combustible charge 80 from a low grade of fuel oil. The water after it leaves the atomizing extremity of the nozzle 49 is further broken and distributed into the cold air, owing to the water being directed against the lower end 85 of the stem 33 of the disk valve 32, in view of the fact that the stem 33 is axially alined with the atomizing extremity of the nozzle 49. In operation a column of hot air passes 90 through the tube 3, and with which column of air, a low grade of fuel oil or gasoline or the like is thoroughly mixed, by being atomized or sprayed thereinto, from the atomizing or spraying end 21. As this mixture of hot air and atomized low grade oil 95 or gasoline enters the mixing chamber 4, combined cold air and an atomized or fine mist of water is drawn past the valve 32 into the chamber 4 and mixed therewith, thereby forming a combustible charge suitable to be introduced into a combustion chamber, of an internal combustion engine, the valve 27 constituting means to control 100 the amount of charge to be drawn into said combustion chamber.

The invention having been set forth, what is claimed as new and useful is:

1. In a carbureter, a casing having a mixing chamber, means for introducing a column of heated air into said chamber, a liquid fuel reservoir surrounding the column of heated air, means for introducing fuel into the column of heated air to pass into the mixing chamber, and means for introducing combined cold air and a small quantity of water into said mixing chamber, and means for confining the heated air in a column until and as it enters the mixing chamber.

2. In a carbureter, a casing having a mixing chamber, means for introducing a column of heated air into said chamber, a liquid fuel reservoir surrounding the column of heated air, means for introducing fuel into the column of heated air to pass into the mixing chamber, and means for introducing combined cold air and a small quantity of water into said mixing chamber, and means for atomizing the fuel, and means for confining the heated air in a column

- until and as it enters the mixing chamber, said fuel atomizing means extending into the confining means.
3. In a carbureter, a casing having a mixing chamber, means for introducing a column of heated air into said chamber, a liquid fuel reservoir surrounding the column of heated air, means for introducing fuel into the column of heated air to pass into the mixing chamber, and means for introducing combined cold air and a small quantity of water into said mixing chamber, and means for confining the heated air in a column until and as it enters the mixing chamber, said confining means comprising a tube extending into the mixing chamber.
4. In a carbureter, a casing having a mixing chamber, means for introducing a column of heated air into said chamber, a liquid fuel reservoir surrounding the column of heated air, means for introducing fuel into the column of heated air to pass into the mixing chamber, said casing consisting of two parts, means comprising a tube for confining the heated air in a column until and as it enters the mixing chamber, said tube having a flange clamped between said two parts of the casing, means consisting of an atomizer extending into the tube for atomizing the fuel into the column of air, means for introducing combined cold air and a small quantity of water into said mixing chamber, and means for atomizing the water.
5. In a carbureter, a casing having a mixing chamber, a liquid fuel reservoir fixed to said casing, a tube extending axially of said casing and having means fixed between the reservoir and the casing, said reservoir having an interior wall forming a passage in communication with and conveying hot air through said tube into said mixing chamber, means for introducing atomized fuel from the reservoir into said column of hot air of said tube, and means responsive to the suction strokes of an engine for permitting the introduction of combined cold air and the fine mist into said mixing chamber.
6. In a carbureter, a casing having a mixing chamber, a liquid fuel reservoir fixed to said casing, a tube extending axially of said casing and having means fixed between the reservoir and the casing, said reservoir having an interior wall forming a passage in communication with and conveying hot air through said tube into said mixing chamber, means for introducing atomized fuel from the reservoir into said column of hot air of said tube, and means responsive to the suction strokes of an engine for permitting the introduction of combined cold air and the fine mist into said mixing chamber, said last named means comprising a valve responsive to the suction stroke of the engine, and means for atomizing water into said cold air.
7. In a carbureter, a casing having a mixing chamber, a liquid fuel reservoir secured to said casing, a tube arranged axially of the mixing chamber and having a flange secured between the reservoir and said casing, said reservoir having an interior wall forming a passage for introducing hot air through said tube into said mixing chamber, one wall of the reservoir having a duct in communication with the interior of the reservoir, a needle valve to control the fuel from the reservoir into said duct, said duct having means to atomize said fuel into the hot air as it passes through the tube, a cold air passage in communication with the mixing chamber, a valve controlling the communication between the cold air passage and the mixing chamber and being responsive to the suction strokes of an engine to permit cold air to enter the mixing chamber, and a nozzle disposed axially with the stem of the valve for atomizing water into said cold air.

In testimony whereof I have signed my name to this specification in the presence of two subscribing witnesses.
